UNITED STATES PATENT OFFICE.

JOHN JOSEPH McGUIRL, OF MONACA, PENNSYLVANIA, ASSIGNOR OF ONE-THIRD TO
MIKE HAPACH, OF COLONA, PENNSYLVANIA.

METALLIC TIE AND RAIL-FASTENER.

1,002,070.

Specification of Letters Patent. Patented Aug. 29, 1911.

Application filed May 29, 1911. Serial No. 629,989.

To all whom it may concern:

Be it known that I, JOHN JOSEPH McGUIRL, a citizen of the United States of America, residing at Monaca, in the county of Beaver and State of Pennsylvania, have invented certain new and useful Improvements in Metallic Ties and Rail-Fasteners, of which the following is a specification, reference being had therein to the accompanying drawing.

This invention relates to metallic ties and rail fasteners, and the objects of my invention are to provide a light and durable cross tie at a minimum cost, and to provide a tie having the requisite amount of elasticity to prevent injury to rolling stock passing over the same.

Other objects of my invention are to provide a tie having a bearing surface possessing the necessary area for the adequate support of rails, and to provide a tie that can be easily and quickly installed and tamped in a roadbed by unskilled labor.

Further objects of my invention are to furnish a metallic tie with a fastener that can be readily adjusted to compensate for wear, and to provide a fastener that will prevent lateral and vertical displacement and preserve the proper alignment and gage of the rails of a track.

Still further objects of my invention are to obviate the necessity of using bolts and nuts for connecting splice bars or fasteners to rails, and to provide a rail fastener that is durable and highly efficient for the purposes for which it is intended.

I attain the above objects by a mechanical construction that will be hereinafter specifically described and then claimed, and reference will now be had to the drawing, wherein:—

Figure 1 is a side elevation of a tie in accordance with this invention, partly broken away and partly in section, Fig. 2 is a plan of the same, Fig. 3 is a perspective view of a detached outer rail fastener, and Fig. 4 is a cross sectional view of a turnbuckle adapted to form part of the fastener, showing a wrench or instrument for operating the same.

A tie in accordance with this invention comprises an inverted channel-shaped bar having a top plate 1, side walls 2 and lateral flanges 3, said bar corresponding in length to the present type of wooden tie. The

lateral flanges 3 are located at the lower edges of the side walls 2, and these flanges, together with the lower edges of the side walls 2 are cut away, as at 4 to accommodate transverse tie plates 5 adapted to assist in supporting the tie directly beneath the rails mounted thereon. The tie plates 5 snugly fit the walls of the cut away portions of the flanges in the side walls. If desired however, the plates 5 can be secured in position by any suitable means other than that as stated. The plates 5 coöperate with the flanges 3 to prevent the tie from sinking to a great depth in the ballast of the roadbed, and when the ballast of the roadbed engages the plate 5 between the walls 2, said plates prevent creeping or shifting of the tie upon the roadbed.

The top plate 1 intermediate the ends thereof is provided with a rectangular opening 6 and adjacent to each end with a longitudinal slot 7; the outer end of each slot being enlarged to provide an opening 8, for a purpose that will presently appear.

Mounted upon the top plate 1 over the inner ends of the slot 7 are the base flanges 9 of rails 10. Engaging the inner sides of the rails 10 are inner fasteners, comprising splice bars 11 having the lateral flanges 12 thereof provided with depending arms 13 and these arms have the lower ends thereof provided with lateral extensions 14 in a plane parallel with the top plate 1. The arms 13 are provided with openings 15 having the outer ends thereof enlarged and screw threaded, as at 16 to receive the outer ends of tubes 17. The inner ends of the tubes are closed by washers 18 and arranged longitudinally of said tubes are tie rods 19. The inner ends of the tie rods 19 are screw threaded and have free movement in the washers 18, and screwed into the ends of the turnbuckle 20. The turnbuckle 20 is hollow, as at 21 to provide clearance for the inner ends of the tie rods, and centrally of the turnbuckle, the periphery thereof is provided with teeth 22, these teeth being directly beneath the openings 6 of the top plate 1.

Adapted to brace the outer sides of the rails 10 are outer fasteners, comprising splice bars 23 having the lateral flanges 24 thereof provided with depending arms 25 similar to the arms 13. The arms 25 have longitudinal openings 26 and transverse

openings 27. Heads 28 are arranged in the openings 27 and adapted to extend through said heads and the openings 26 are the outer ends of the tie rods 19. The heads 28 are 5 secured to the outer ends of the tie rods 19 by pins or other fastening means 29. The lower ends of the arms 25 have lateral extensions 30 provided with longitudinal openings 31, which are screw threaded for longitudinal bolts 32, said bolts having the threaded inner ends thereof bearing against the extensions 14 of the inner fasteners and the outer ends thereof provided with rectangular heads 33.

15 A suitable instrument can be employed for adjusting the turnbuckle, and a conventional form of instrument is shown in Figs. 1 and 4, wherein a yoke 34 has bifurcated arms 35 adapted to rest upon the turnbuckle 20 at the sides or ends of the teeth 22. In the yoke 34 is fixed by a pin 36 or other fastening means an operating lever or arm 37. This lever extends through the yoke and has the lower end thereof bifurcated, as at 38 for 25 a pivoted pawl 39 adapted to engage the teeth 22 of the turnbuckle and rotate said buckle in a desired direction when the operating lever 37 is oscillated. The openings 6 provide clearance for the instrument and I 30 would have it understood that the invention is not limited to this particular type of adjusting instrument.

In assembling the parts of the rail fastener, the inner fasteners are first placed in 35 position through the medium of the slots 7 and the openings 8. The parts of the turnbuckle are then assembled and connected to the inner fastener, and then the rails 10 are placed in position. The outer fasteners are 40 then placed in position and connected to the outer ends of the tie rods 19. The screws 32 can then be placed in position from the ends of the tie. By oscillating the operating lever 37, the turnbuckle can be 45 rotated to draw inwardly upon the tie rods 19 and this movement of the tie rods binds the inner fasteners in the inner ends of the slots 7, the rails 10 against the inner fasteners, and the outer fasteners against 50 the outer sides of the rails. The rails will be firmly held and anchored upon the tie. The screws 32 are employed to assist in 55 disassembling the rails, especially should one of the tie rods 19 break at a point adjacent to the turnbuckle by screwing inwardly

upon the teeth 22, the outer fastener will be forced outwardly relatively to the inner fastener and can be easily removed. It is obvious that the other parts of the fastener can be readily disassembled.

60 The washers 18 are adapted to prevent the ends of the turnbuckle from moving or wearing on the inner ends of the tubes 17 when the turnbuckle is rotated, and the tubes 17 prevent the tie rods from being injured 65 or interfered with by the ballast of a roadbed.

What I claim is:—

1. In a metallic tie and rail fastener, an inverted channel-shaped bar adapted to 70 support rails, said bar having the top plate thereof provided with openings, inner and outer fasteners bracing the sides of said rails and extending into said tie, tubes carried by the inner fasteners within said tie, 75 tie rods extending through said tubes and having the outer ends thereof anchored in the outer rail fasteners, a turnbuckle connecting the inner ends of said tie rods at a point beneath one of the openings of said 80 tie, and means including screws carried by the outer rail fasteners adapted to facilitate the disassembling of said rail fasteners.

2. In a metallic tie and rail fastener, an inverted channel-shaped bar having the top 85 plate thereof provided with openings and adapted to support rails, inner splice bars adapted to engage the inner sides of the rails and having depending arms extending through some of the openings of said tie, 90 tubes carried by the arms of said inner splice bars, outer splice bars adapted to engage the outer sides of the rails and having depending arms extending into said tie, tie rods arranged longitudinally of said tubes 95 and having the outer ends thereof anchored in the arms of the outer splice bars, a turnbuckle connecting the inner ends of said tie rods at a point below the other openings of said tie, and screws carried by the arms of 100 the outer splice bars and adapted to engage the arms of the inner splice bars and facilitate the disassembling of the rail fasteners.

In testimony whereof I affix my signature in the presence of two witnesses.

JOHN JOSEPH McGUIRL.
